UNITED STATES PATENT OFFICE

1,934,252

BIT ROTATING DEVICE FOR RECIPROCATING TOOLS

James N. Baker, Towson, Md., assignor to The Black & Decker Manufacturing Company, a corporation of Maryland

Application February 2, 1931. Serial No. 512,800

7 Claims. (Cl. 255—43)

The invention relates to an automatic turning device which is adapted for use with a percussive tool or portable power-driven hammer, being particularly useful in turning a drill bit or the like operated by such a hammer or any type of reciprocating tool.

While the turning device is illustrated in connection with a hammer of a type in which the striker element is driven in reciprocation by a motor-operated rotary crank and connecting rod, its use and application are by no means and in no way limited to this or any other type of hammer or percussive tool.

While the turning device is especially useful in connection with a star or similar drill or bit serving to rotate the drill as it is struck by the hammer, thus preventing clogging due to the accumulation of particles of cement, stone, etc., previously loosened by the drill, the invention is not limited in its application to this or any particular type of bit.

In the accompanying drawings I have illustrated a turning device embodying the features of the invention in the preferred form, the same being shown in connection with so much of a portable power-driven hammer as is necessary to a full understanding of the method of constructing, applying, operating and using the turning device.

30 In the drawings—

Figure 1 is a side elevation of a portable hammer selected for convenience as a vehicle for the illustration of the invention, the same being equipped with the turning device of the invention.

Figure 2 is a vertical central section taken on the axis of the hammer and broken away intermediately to shorten the structure for convenience of illustration.

40 Figure 3 is a section on the same line at right angles to Figure 2, certain of the parts within the hammer barrel being shown in elevation.

Figure 4 is a transverse section on the line 4, 4 of Figure 2.

45 Figure 5 is a fragmentary elevation showing one of the pawls and the manner of mounting and engaging the same, including the pawl carrier and ratchet.

Referring to the drawings by numerals, each 50 of which is used to indicate the same or similar parts in the different figures, the portable power-driven hammer, to which the invention is applied for purposes of illustration, consists of a hammer or gear case 1 to which is attached a barrel 2, and grip 4. The working parts include,

in the form of hammer shown, an electric motor 5 which drives through bevel gear 6 and pinion 7 a crank shaft 8 which operates a connecting rod 9 and piston rod or thrust rod 10, which in turn reciprocates a pistonlike ram or striker member 11 which is shown as connected to the thrust rod or piston rod 10 by way of and by means of springs 12. The details of the hammer structure shown are, as already pointed out, in no way material to the present invention, being 60 shown merely to illustrate the application of the device to a convenient type of hammer.

The turning device in the preferred form, as shown, comprises a sleeve or tube 15 which is mounted to rotate or oscillate within the barrel 2 and within which the piston or ram 11 slides and reciprocates in the operation of the hammer. This sleeve 15 is secured at its upper end to a collar 16, referred to hereinafter as the ratchet or ratchet collar, the same being provided with ratchet teeth 17 on its upper edge extending entirely around its periphery. This collar rests and rotates on an upwardly disposed annular shoulder or shelf 18, the same comprising in the form of the invention shown a portion of the upper surface of the barrel 2 where it projects inwardly from the lower edge of the gear or hammer casing 1 to which it is attached by flange 21. Tool bushing 20 is secured to the lower end of the sleeve or tube 15, and is suitably guided by engagement with a bearing surface 22 formed on the inside of the barrel for this purpose.

55 In the form of the invention shown the sleeve 15 has a threaded connection with the ratchet collar 16 and with the tool bushing 20, respectively, being threaded into the inside of ratchet collar 16 at 16' and receiving the tool bushing 20 within the internal thread 23, but these parts may be held in similar relation in any suitable and convenient manner. The tool bushing 20 is apertured centrally at 24 in line with the axis, the aperture being adapted to fit the shank 25 of the drill or other bit and to hold the same in such manner as to prevent or substantially prevent rotation of the drill relatively to the bushing, or otherwise to cause the drill to rotate with the bushing.

60 The ratchet collar 16 is rotatably supported, as already described, at the lower end of the hammer casing or gear casing 1 or a suitable extension 1' thereof which may be chambered at 26 for this purpose, providing a downwardly disposed annular shoulder 27 spaced well above the shoulder 18 already described. An internally shouldered 105

spring abutment ring 28 is pressed up against this shoulder by the relief spring 29 which may be otherwise referred to as the actuating spring of the rotative device.

Between the spring abutment ring 28 and the ratchet collar 16 is a pawl carrier or cylinder 30. This bears at its upper end against an outer downwardly disposed peripheral shoulder 31 on the spring abutment ring 28, and at its lower end it may rest on the ratchet teeth 17 or be otherwise suitably supported. This pawl-carrying sleeve or cylinder 30 is provided at its lower end with pawls 32, see particularly Figure 5. These pawls as shown are provided with circular heads 33 mounted in circular sockets 34 formed in the wall of the pawl-carrying cylinder 30 near the lower edge. The pawls 32 project downwardly from these sockets into and beyond slots 35 formed in the lower edge of the cylinder for this purpose and connected to the sockets. The pawls are urged downwardly into engagement with the teeth 17 of the ratchet collar 16 by springs 36. The pawl carrier 30 is also slotted diagonally at 38, Figure 3, the slot being inclined to the right and extending upwardly from the bottom edge of the carrier. This slot is engaged by a pin 39 projecting outwardly from the spring enclosing sleeve 40 which is located within the carrier and shouldered at its bottom edge at 41 to support the spring 29, the sleeve 40 in turn resting at its lower edge on an annular shoulder 42 formed on and near the upper portion of the ratchet collar 16. This spring sleeve 40 is permitted to slide vertically, being normally held down by tension of spring 29 and is held against rotation by an anchor screw 44 which is driven through the gear casing or hammer casing 1 for this purpose, and engages a vertical slot 45 in the spring sleeve 40. This anchor screw 44 also passes through a relatively wide slot 46 in the pawl carrier 30 and limits the rotation of the latter. Shoulder 41 is formed on an inwardly disposed flange 47 which projects into the upward or retraction path of the ram.

In the operation of the hammer the ram or striker on its retraction or upward stroke contacts the ledge or flange 47 at the lower end of the spring sleeve 40, forcing the sleeve upward against the tension of the spring 29 and tending to close the space 48 between the spring sleeve and the collar 28 where a sufficient clearance is provided. This upward motion of the spring sleeve which is held against rotation by the anchor screw 44 and the slot 45 engaged thereby, as it raises the pin 39 in a vertical direction, serves by engagement of this pin 39 with the inclined slot 38, which may be otherwise termed a cam slot in that it has a camlike operation, to rotate the pawl carrier in clockwise direction, in accordance with the form of the invention shown, the motion of the carrier being limited by the inclination of the slot 38 and also by the width of the slot 46 in the carrier as shown in Figure 4.

This clockwise rotation or oscillation of the carrier 30 causes the pawls 32 to engage the ratchet teeth 17 moving the ratchet collar 16 and hence the sleeve 15, tool bushing 20 and the tool 25 in clockwise rotation through an arc corresponding to the upward motion of the spring sleeve 40 and the inclination of the cam slot 38 in the carrier 30. When the ram 11 again moves downwardly on the working stroke, the spring sleeve 40 is released and moves downwardly in response to the tension of the spring 29. On this return motion of the sleeve, the pin 39 engages

the opposite side of the slot 38, rotating the pawl carrier 30 through a corresponding step or oscillation in the opposite and in this instance in contra-clockwise direction, drawing the pawls 32 backwardly over the ratchet teeth 17 so that they are ready on the next upward or retraction stroke of the ram to re-engage the ratchet teeth and move the collar 16, the sleeve 15, the tool bushing 20 and the tool 25 through a second step in clockwise rotation. By constant repetition of this operation which is incident to the operation of the hammer, a step by step rotation is thus imparted to the tool, giving the desired automatic rotation of the tool whereby the tendency to clog with particles of cement, stone, etc. is completely overcome and the edges are presented in new cutting positions to new portions of the material being cut.

I have thus described the preferred form of my invention for providing an automatic turning movement of the tool operated by a power hammer or the like, the description being specific as to the details in order that the manner of constructing the invention in the preferred form, and operating, applying and using the same may be fully understood; however, the specific terms herein are used descriptively rather than in a limiting sense, the scope of the invention being defined in the claims.

What I claim as new and desire to secure by Letters Patent is:

1. The combination with a power hammer having a reciprocating ram of a spring having an abutment spaced backwardly from the ram in the direction of the retraction stroke, an opposite, yielding abutment for said spring in the path of the ram on said stroke whereby said yielding abutment is reciprocated by the ram and spring, means for preventing rotation of said yielding abutment, a rotary pawl carrier and pawls, means for imparting an oscillating motion to said pawl carrier from said yielding abutment as it reciprocates, a ratchet rotated by the pawls and receiving a step by step rotation therefrom, a tool bushing and means connecting the ratchet to the tool bushing to rotate the latter.

2. The combination with a power hammer having a reciprocating ram of a spring having an abutment spaced backwardly from the ram in the direction of the retraction stroke, an opposite yielding abutment for said spring in the path of the ram on said stroke whereby said yielding abutment is reciprocated by the ram and spring, means for preventing rotation of said yielding abutment, a rotary pawl carrier and pawls, means for imparting an oscillating motion to said pawl carrier from said yielding abutment as it reciprocates, a ratchet rotated by the pawls and receiving a step by step rotation therefrom, a tool bushing and means connecting the ratchet to the tool bushing to rotate the latter, said connecting means being in the form of a tube enclosing the ram.

3. The combination with a power hammer having a reciprocating striking member of a spring pressed abutment moved in opposition to the spring by the retraction stroke of the striking member, said abutment being returned by the action of the spring, means for preventing rotation of said abutment, a pawl carrier, means for oscillating said pawl carrier from said abutment, means for limiting the motion of the carrier, pawls carried thereby, a ratchet ring receiving a step by step rotation from said pawls, a tube secured at one end to the ratchet ring and encir-

cling the striker, and a tool bushing secured to the other end of said tube.

4. The combination with a power hammer having a reciprocating ram of a spring pressed member moved in opposition to the spring by the retraction stroke of the ram, said member being returned by the action of the spring, means for preventing rotation of said member, a pawl carrier, means for oscillating said pawl carrier from 10 said member, means for limiting the oscillatory motion of the pawl carrier, pawls carried thereby, a ratchet receiving a step by step rotation from said pawls, a tube secured at one end to the ratchet and encircling the striker, a tool bushing 15 secured to the other end of said tube and an abutment supporting said spring oppositely to said member, said abutment and said ratchet serving as opposed stops for preventing motion 20 of the pawl carrier in the direction of reciprocation of the ram.

5. The combination in a portable power hammer having a reciprocating ram of a member in the path of the ram to be operated by the return stroke of the ram to move in the direction of retraction of the ram, a spring moving said member in the opposite direction whereby said member is reciprocated in the direction of the path of the ram, means for oscillating said member about the axis of the ram as it is thus reciprocated, and ratchet and pawl mechanism operated by said member as it oscillates to impart a step by step 30 rotary motion to the tool.

6. The combination in a portable power hammer having a reciprocating ram of means in the form of a sleeve in the path of the ram to be operated by the return stroke of the ram to move in the direction of retraction of the ram, a spring moving said sleeve in the opposite direction, whereby said sleeve is reciprocated in the direction of the path of the ram, means for oscillating said sleeve about the axis of the ram as it is thus reciprocated, and means comprising a ratchet and pawl mechanism operated by said sleeve and a ram guide carrying a tool support at one end and one element of said ratchet and pawl mechanism at the other end for communicating a step by step rotary motion to the tool.

7. The combination in a portable power hammer having a reciprocating ram of means in the form of a sleeve in the path of the ram to be operated by the return stroke of the ram to move in the direction of retraction of the ram, a spring moving said sleeve in the opposite direction, whereby it is reciprocated in the direction of the path of the ram, means for oscillating said sleeve about the axis of the ram as it is thus reciprocated, and means comprising a ratchet and pawl mechanism operated by said sleeve and a ram guide in the form of a tubular member carrying a tool support at one end and one element of said ratchet and pawl mechanism at the other end for communicating a step by step rotary motion to the tool.
